GREASE DISPENSING DEVICE

Filed Jan. 13, 1937

Inventor:

Arthur I. Epton

by Max Richard Evans

Atty.

UNITED STATES PATENT OFFICE

103,491

DESIGN FOR A GREASE DISPENSING DEVICE

Arthur I. Epton, Chicago, Ill.

Application January 13, 1937, Serial No. 67,030

Term of patent 7 years

To all whom it may concern:

Be it known that I, Arthur I. Epton, a citizen of the United States, residing at Chicago, in the county of Cook and State of Illinois, have invented a new, original, and ornamental Design for a Grease Dispensing Device, of which the following is a specification, reference being had to the accompanying drawing, forming part thereof.

The figure is a perspective view of a grease dispensing device showing my new design.

I claim:

The ornamental design for a grease dispensing device, as shown.

ARTHUR I. EPTON.
